Primary Examiner — Marianne Pandozzi

(57) **CLAIM**

The ornamental design for a mug, as shown and as described.

DESCRIPTION

FIG. 1 is a perspective view of a mug showing my new design; FIG. 2 is a rear perspective view thereof; FIG. 3 is a rear view thereof; FIG. 4 is side view thereof; and, FIG. 5 is top view thereof.

The broken lines are for illustration purposes only and form no part of the claimed design.
